Primary Examiner — Charles Hanson(74) *Attorney, Agent, or Firm* — ClearPat Services, LLC(57) **CLAIM**

The ornamental design for a spinal disc implant with conic protrusions, as shown and described.

DESCRIPTION

FIG. 1 is a side elevation view showing our new design of a spinal disc implant with conic protrusions;

FIG. 2 is a side elevation view of FIG. 1 turned 90 degrees;

FIG. 3 is a bottom perspective view of FIG. 1;

FIG. 4 is a bottom plan elevation view of FIG. 1;

FIG. 5 is a top perspective view of FIG. 1; and,

FIG. 6 is an alternate embodiment of FIG. 3.
